UNITED STATES PATENT OFFICE.

MAURICE J. HOFFENBERG, OF NEW YORK, N. Y.

WINDOW-SASH STARTER.

Application filed June 2, 1925. Serial No. 34,279.

This invention relates to devices for starting and lifting window sashes and is particularly adapted to be applied to windows for railway passenger cars, dwellings and the like.

Much difficulty is generally experienced in raising slideable window sashes due to sticking, and after they have been left undisturbed for a time in a lowered position.

10 An object of the invention is to provide a practical device for effectively overcoming this difficulty and which may be readily attached to a slideable window sash to provide improved means whereby a powerful force may be easily applied for prying and moving the sash.

Another object of the invention is to provide a device of the character described which comprises few and simple parts, which 20 is simple in construction, comparatively inexpensive to manufacture, and is efficient in operation to a high degree.

Other objects of this invention will in part be obvious and in part hereinafter pointed out.

Certain features herein shown and described are shown, described and claimed in my co-pending application Serial No. 730,388 filed August 6th, 1924.

30 The invention accordingly consists in the features of construction, combinations of elements and arrangement of parts which will be exemplified in the construction hereinafter described and of which the scope 35 of application will be indicated in the following claims.

In the accompanying drawing, in which is shown one of the various possible illustrative embodiments of this invention,

40 Figs. 1 and 2 are fragmentary perspective views of window frames and sashes each having a device embodying the invention applied thereto, the former showing the sash closed and the latter showing the 45 sash partially open after operation of the device;

Fig. 3 is an elevational view looking at the rear side of my device to show the interior construction; and

50 Fig. 4 is a cross-sectional view taken on line 4-4 in Fig. 3.

Referring in detail to the drawing, 10 indicates in general a window starting and lifting device embodying the invention which may be attached in any convenient

position on the lower cross member 11^a of a vertically slideable window sash 11. Preferably, the device 10 is attached on a midportion of said member so that the usual corner window stop latch 12 and said device 10 may be readily operated together as will hereinafter be explained and so that the device will be very effective to overcome the worst binding condition of the sash 11.

60 The stop latch 12 may be of any standard construction and is seen to include the usual finger lever 12^a which actuates the disengagement of a latch 12^b with a tooth rack 13 on an upright 14^a of the window 70 frame 14 in the well known manner.

65 The device 15 may comprise a casing 16 having means of suitable construction to firmly secure the device to the sash such as ear 15^a and holes 15^b adapted to receive 75 screws 17. Pivotally mounted on the casing 16 is a hand lever 18 having the handle end 18^a extending along the exterior side thereof, said lever having a recess on its under side, as at 18^b for receiving the fingers of the operator. The pivoted end 18^c of said lever projects through to the interior of the casing 16 and is constructed to support a sector gear member 19 having gear teeth 19^a as shown in Fig. 4. The 80 portion 18^a of the lever end 18^c on which the member 19 is mounted is preferably made to have a non-circular cross-section and is shaped to snugly fit into a similar shaped hole 19^b in the gear member 19 90 so that the latter is actuated on movement of the lever 18.

85 For holding the gear member 19 on the lever end 18^c, a washer 20 seated in a recess 19^c of said member 19 is provided, said 95 washer being secured to a stub projection 18^e which may be riveted over to hold the washer 20 and gear member 19 against displacement, as shown in Fig. 4.

Engaging the teeth 19^a of gear 19, is a 100 rack 21^a preferably formed integral with a sliding plunger bolt 21. On swinging the lever 18 from the position shown in full lines in Fig. 3 to that shown in dotted lines, the plunger bolt 21 is caused to move out 105 of the casing 16 to the position shown in dotted lines. Suitable stop means such as a lug 22 may be provided for limiting the movement or downward throw of the gear member 19, and a suitable guide projection 110

23 extending from the casing may be provided for preventing the plunger bolt 21 from accidental displacement from its proper path of movement.

5 In using the invention with the parts positioned as shown in Fig. 1, the spring stop latch 12 is released and at the same time the lever 18 is lifted. The latter operation is effective to apply a direct force to raise 10 the window sash and to simultaneously provide a powerful prying action of the plunger bolt 21 on the sill 14^b of the window frame 14 for moving the sash 11 with respect to said frame.

15 Releasing the lever 18 returns the parts to their normal retracted position shown in full lines in Fig. 3 and the window may be left in an opened or closed position as desired. If the window is left closed the device is 20 again ready for operation in the manner above described.

Because of the construction of the device and its arrangement on the window sash as 25 above described, it is obvious that said device provides a simple means for applying a pressure which is sufficiently powerful and effective for starting windows and is capable of overcoming comparatively strong binding conditions.

30 It will thus be seen that there is provided a device in which the several objects of this invention are achieved and which is well adapted to meet the conditions of practical use:

35 As various possible embodiments might be made of the above invention, and as various changes might be made in the embodiment above set forth, it is to be understood that all matter herein set forth or shown 40 in the accompanying drawing is to be interpreted as illustrative and not in a limiting sense.

Having thus described my invention, I claim as new and desire to secure by Letters Patent:—

45 1. A window sash starting and lifting device comprising a casing, a plunger bolt and a gear for actuating said bolt in said casing, said casing, bolt and gear carried by the sash, the sash and the entire device

being adapted to move with respect to the window sill.

2. A window sash starting and lifting device secured to move as a unit with the sash comprising a segmental gear member and 55 a plunger bolt having a rack meshing with said gear member, said bolt adapted to engage the sill of the window on actuation of said member for moving the window sash and the entire device with respect to said 60 sill.

3. A window sash starting and lifting device secured to move as a unit with the sash comprising a segmental gear member, a 65 plunger bolt having a rack meshing with said gear member, and a hand lever for actuating said gear member, said bolt adapted to engage the sill of the window on actuation of said member for moving the window sash and the entire device with respect 70 to said sill.

4. In combination with a vertically sliding window, a window sash starting and lifting device secured to move with the sash comprising a segmental gear member, a 75 plunger bolt having a rack meshing with said gear member, and a pivoted hand lever secured to said gear member, said lever and member co-operating to actuate the plunger bolt on the application of a lifting force to the lever, said bolt adapted to engage the sill of the window on actuation of said member for moving the window sash and the entire device with respect to said 80 sill.

5. In combination with a vertically sliding window, a window sash starting and lifting device secured to move with the sash comprising a casing, a sector gear member pivoted in said casing, a plunger bolt having a rack meshing with said member, and a 90 hand lever having a recess formed therein to receive the operator's fingers, said lever co-operating with the gear member to actuate the plunger bolt on applying a lifting force on the lever for raising the window 95 sash with the entire device.

In testimony whereof I affix my signature.

MAURICE J. HOFFENBERG.
